ATTORNEY

a single piece of paper 8 coiled to the desired conical shape, and including inner and outer laps. The tabs 9 are formed by punching them from the outer lap of the container 8.

5 In operating the device, when a cup of tea is to be served, the wire attachment is secured to the edge of the saucer by means of the clamping members 3, and a paper container is pushed into the supporting ring 2 until it is interlocked therewith, and the tea ball is placed within the paper container 5. The tea ball can be placed in the cup of hot water and removed as often as desired, and when not in use is kept in the paper container 5. When the tea ball is to be used no longer, the paper container with the tea ball is removed from the supporting ring 2 and can be destroyed, a new container being placed in the supporting ring for each fresh tea ball.

The structure shown may be modified as to various details, without departing from the underlying principles of the improvement, and this application is intended to cover any changes or modifications coming within the purposes of the invention or the scope of the following claims.

I claim:

1. A tea ball holder comprising a vertical portion positionable between the inner and outer edges of the rim of a saucer, a pair of oppositely arranged, symmetrically disposed, U-shaped saucer gripping members extending outwardly from the bottom of said vertical portion around the edge of a saucer and thence under the saucer inwardly, and a container supporting ring extending outwardly from the top of said vertical portion whereby a container positioned

therein has the inner portion of its edge overlying the rim of the saucer and spaced horizontally from the inner edge of said rim.

2. A tea ball holder comprising a single piece of wire including a vertical portion consisting of two strands of wire twisted together and positionable between the outer and inner edges of the rim of a saucer, a pair of oppositely arranged, symmetrically disposed, U-shaped saucer gripping members extending outwardly from the bottom of said vertical portion around the edge of the saucer and thence inwardly under the same, and a container supporting ring extending outwardly from the top of said vertical portion for supporting a container with the innermost portion of the edge of the latter located over the rim of the saucer and spaced horizontally from the inner edge of said rim.

3. The combination with a tea ball holder comprising a single piece of wire including a vertical portion consisting of two strands of wire twisted together and positionable between the inner and outer edges of the rim of a saucer, a pair of angularly and oppositely arranged, symmetrically disposed, U-shaped saucer gripping members extending outwardly from the bottom of said vertical portion around the edge of the saucer and thence inwardly under the same, a container supporting ring extending outwardly from the top of said vertical portion, and a paper container positionable in said ring with the innermost portion of its edge located above the rim of the saucer and spaced horizontally from the inner edge of said rim.
